United States Patent Office

Des. 190,571
Patented June 13, 1961

190,571

LOUNGE CHAIR

Francis M. Mair, Kensington Park, Calif.
(1 Arlington Ave., Berkeley, Calif.)

Filed Dec. 1, 1960, Ser. No. 63,067

Term of patent 14 years

(Cl. D15—11)

Fig. 1

Fig. 2

Fig. 3

This application is a continuation-in-part of my earlier filed application Serial No. D. 57,680, filed September 25, 1959, which is now abandoned.

I claim:

The ornamental design for a lounge chair, as shown and described.
